UNITED STATES PATENT OFFICE

2,466,355

DETENT MECHANISM FOR PRESSURE REGULATORS

Fred J. Wright, Upper Arlington, Ohio, assignor,
by mesne assignments, to The Jeffrey Manufacturing Company, a corporation of Ohio

Application July 20, 1944, Serial No. 545,836

2 Claims. (Cl. 74—527)

1

This invention relates to a pressure regulator or unloading valve particularly adapted to control the pressure in an accumulator.

An object of the invention is to provide an improved detent, usable as a separate unit, and also as an element of an improved unloading valve.

Other objects of the invention will appear hereinafter, the novel features and combinations being set forth in the appended claims.

In the accompanying drawings,

Fig. 1 is a perspective view of the valve of my invention;

Fig. 2 is a longitudinal sectional view through said valve;

Fig. 3 is a sectional view taken on the line 3—3 of Fig. 2, looking in the direction of the arrows; and

Fig. 4 is a piping diagram of a hydraulic system incorporating my valve.

Referring first to Fig. 4 of the drawings, I shall describe the illustrated hydraulic system which incorporates my valve as an important element thereof. A motor driven pumping unit 24 provides the primary source of hydraulic fluid under pressure which is delivered by the pump of said unit to a pressure line 1. The pressure line 1 leads to the unloading or pressure regulating valve of my invention which is designated generally by the reference character 30. The unloading valve 30 functions so that when its control element is in one position, the hydraulic fluid under pressure in the line 1 is delivered to a supply line 2 which leads to an accumulator 23 with a branch leading to a brake control valve 24 which controls the application of hydraulic fluid to a brake piston or motor 22. Drain pipe 4, having two branches, leads from the unloading valve 30 as well as from the control valve 21. Said drain pipe 4 delivers oil at atmospheric pressure to the tank of the pumping unit 24.

In normal operation the pumping unit 24 operates continuously and the regulator valve 30 supplies the hydraulic fluid to the line 2 where it is delivered either directly to the brake piston or motor 22 or to build up a supply in the accumulator 23. Whenever a predetermined pressure is developed in the line 2 in response to a predetermined accumulation of hydraulic fluid in the accumulator 23, the regulator valve 30 operates to provide a substantial no-load by-pass for the pump of the pumping unit 24 or, in other words, it unloads the pumping unit 24. Whenever the pressure in the line 2 reaches a predetermined minimum in response to a predetermined low

quantity of oil in the accumulator 23, the no-load by-pass for the pump is shut off automatically by regulator valve 30 and the hydraulic fluid is again delivered to the line 2, the pumping unit 24 being loaded under these conditions.

Attention is now directed particularly to Figs. 1, 2 and 3 of the drawings and to the detailed structure of the pressure regulating valve 30. Said valve comprises a main body or casting 31 into which the pressure line 1 is threaded and leads into an entry passage or chamber 5. Communicating with the chamber 5 is a bore 32 which leads to an axial cylindrical bore 33 which is the main bore or main cylinder of the casting 31. Within the main cylinder or bore 33 is a piston 42 which is adapted to reciprocate in said bore 33 as hereinafter described.

Removably mounted on the left-hand end of the main casting or body 31, as viewed in Figs. 1 and 2 of the drawings, is a head 34 in the form of a casting which is provided with a chamber or passageway 7 to which a supply pipe 2 is in communication by being threaded into the opening thereof. Leading from the chamber 5 to the chamber 7 is a passageway or bore 6 which is provided with a check valve 35 which normally prevents the flow of fluid from chamber 5 to chamber 7, while normally permitting flow of hydraulic fluid from said chamber 5 to chamber 7 through passageway 6.

Also communicating with the chamber 7 and provided in the head 34 is a cylindrical bore which receives an actuating piston 8 which has a stem extending into the main cylinder or bore 33.

The piston 42 is hollow and through it extends a shoulder pin 10 which carries spaced washers 11 and 111 between shoulders at opposite ends thereof, the shoulder at the left-hand end, as viewed in Fig. 2, being provided by an enlarged head, and the shoulder at the right-hand end being provided by a spacer sleeve 15.

Between the washers 11 and 111 there is a shifter or snap spring 13. Surrounding the central part of the shoulder pin 10 and inside the spring 13 is a spacer tube 14 which limits the compression of the snap spring 13 as hereinafter described. The outer portion of the washer 11 abuts an inner shoulder or ledge on the inside of the piston 42, and the washer 111 abuts a snap ring 16 which snaps into a circular groove on the inside cylindrical surface of the piston 42.

It is, of course, obvious that the actuating piston 8 is subjected to the pressure of the hydraulic fluid in chamber 7 and since the right-hand end thereof abuts the left-hand end of the shoulder

pin 10, this force is transmitted through said pin 10 to a spring guide 18 which is slidably mounted in a head casting 36 removably attached to the main casting 31, as by machine screws.

Within the head casting 36 is a pressure adjusting spring 19 which is compressed by movement of the spring guide 18, the shoulder pin 10, and the piston 8, in response to the hydraulic fluid pressure on said piston 8.

The outer peripheral surface of the piston 12 is provided with a groove or chamber 37 and when the valve parts are in the positions illustrated in Fig. 2 of the drawings, the valve is effectively closed and the hydraulic fluid in chamber 5 is directed through passageway 6 to the supply line 2.

When in response to pressure in chamber 7 the piston or cylinder 12 is moved to the right, as hereinafter described more completely, the piston groove or chamber 37 provides a passageway from chamber 5 through bore 32 to a circumferential chamber 38 formed in the main casting 31 which communicates by means of a bore 39 with the drain pipe 4 so that when said piston 12 is shifted as aforesaid, the pressure line 1 will be connected to the drain pipe 4. Piston 12 is therefore the final control member for the valve 30.

To provide drainage for any leakage and to prevent any development of undesired pressures, particularly on the piston 12, the heads 34 and 36 are provided with drain grooves 40 and 41, respectively, which communicate with the drain pipe 4 by way of longitudinal bore 42 in the main casting 31 which communicates with bore 39.

Adjacent its right-hand end, as viewed in Fig. 2 of the drawings, the piston 12 is provided with a pair of spaced peripheral grooves 20 and 25. The groove 25 is actually open at the right-hand end, but it functions the same as though it were closed as is the groove 20.

The main casting 31 is provided with a peripheral groove 43 which receives a plurality of coil springs 17. These coil springs 17 and associated apparatus co-operate to provide an improved type of detent by which the cylinder 12 is releasably held in either of its two positions, that is, the unloading position or the loading position, and per se and in combination constitutes an important contribution of my invention.

Each of the coil springs 17, if released, would have a straight line longitudinal axis down its center. Each spring, however, is bent so that its longitudinal axis is curved as clearly illustrated in Fig. 3 of the drawings. As a consequence, the center inner portion of each coil spring 17 rides on the bottom of the groove 20 or 25 of piston 12, depending on which is opposite the groove 43. The opposite outer free ends of each coil spring 17 abut the outer periphery or bottom of the groove 43, and the outer portion, as viewed in Fig. 3, is received in the groove 43 and contained within the side walls thereof. The groove 43 has sufficient depth so that when adequate pressure is developed on the piston 12 to move it, for example, to the right from the position illustrated in Fig. 2 of the drawings, each spring 17 can be deflected, bent or flexed so that its longitudinal axis is bent into an arc of smaller radius, and the outer central portion of each said spring 17 pressed into said groove 43 while the inner central portion of each rides over the projection between the two adjacent grooves 20 and 25.

Considering this structure in a slightly different manner and referring particularly to Figs. 75

2 and 3 of the drawings, it is to be noted that the axes of the coil spring 17 lie in a plane which is at right angles to the axis of the piston 12. When these springs 17 are acting to retain the piston

12 releasably in either position, the central inner portion of each coil spring is received in a groove 20 or 25 while at least a portion of the entire outer part of each spring, measured radially from the axis of piston 12, extends in the groove 43. However, the outer central part of each spring 17 is spaced inwardly from the bottom of the groove 43 or, in other words, from the outer peripheral wall thereof. Furthermore, the axis of each spring 17 is on a curve, the diameter of which is greater than the diameter of the groove 43. As the piston 12 moves and the inner portion of each spring 17 is deflected radially outwardly, its axis bends into a circle of smaller diameter and practically the entire outer peripheral surface of each spring 17 is in contact with the bottom or outer peripheral wall of the groove 43, while each spring 17 is relatively free to roll in the groove 43.

In the operation of the pressure regulator, if the pressure in the accumulator 23 and that in the line 2 are below a predetermined maximum, the valve piston 12 will be in the position illustrated in Fig. 2 of the drawings. Hydraulic fluid under pressure will be flowing through the pressure line 1 into the chamber 5 through passageway 6 and past check valve 35 which will be open, to the supply line 2 from which it will flow to the accumulator or directly to the brake piston 22 if the valve 21 is actuated to operate it.

As the pressure builds up, due to the delivery of a great amount of fluid to the accumulator 23, this pressure will be communicated to the piston 8 through the chamber 7 and force the piston 8, shoulder pin 10 and spring guide 18 to the right, as viewed in Fig. 2 of the drawings, to cause compression of the pressure adjusting spring 19. This movement will take place for a time without moving the piston 12 from the position illustrated, and this movement of the pin 10 will cause compression of the shifter or snap spring 13 since the washer 11 will move with the pin 10, and the opposite or right-hand end of the spring 13 is held against the abutting washer 111 to the piston 12 by means of snap ring 16.

After a predetermined movement of the pin 10 to the right from that illustrated in Fig. 2 of the drawings, the spacer tube 14 will abut or strike the washer 111, and further movement of said pin 10 to the right as controlled by piston 8 against the compression of spring 19, will force movement of the piston 12 to the right. During the compression of the snap spring 13 the piston 12 is held in the position illustrated in Fig. 2 of the drawings, by the detent formed by the coil springs 17, the groove 43 which receives it, and the open end groove 25.

As the piston 12 is moved to the right, as above described, the ledge between the grooves 25 and 20 will force the centers of the coil springs 17 outwardly into the groove 43 or, in other words, bend or deflect them, and once this movement is started, the energy stored up in the snap spring 13 will cause the piston 12 to move with a snap action to the right, and the center portions of the coil springs 17 will deflect or bend outwardly as said coil springs 17 roll by a distinct rolling action over the peripheral projection of the piston 12 between the grooves 20 and 25.

It may be noted that this rolling action of the

springs 17 provides for a minimum of wear of said springs as well as of the other detent mechanism, including adjacent portions of piston 12. Each spring 17 also contributes to a long life and a minimum of wear by virtue of the further fact that it has a large area of contact with the bottoms of the grooves 20 or 25 as well as a large area of contact with the ridge of piston 12 between said grooves as to which it comes into rolling contact as the piston 12 shifts.

The aforesaid snap action to the right will continue until groove 20 of the piston 12 is opposite the groove 43 of the main body 31, in which position the springs 17 will be received in the grooves 20 and the piston 12 will be releasably detained or held in the by-pass or unloading position thereof.

As previously mentioned, when this shifting action has taken place in response to the accumulation of a predetermined amount of fluid in the accumulator 23, or, in other words, a predetermined pressure in supply line 2, the piston 12 provides an unloading of the pumping unit 24 by providing a by-pass between the pressure line 1 and the drain pipe 4 by way of chamber 5, bore 32, chamber 37 in piston 12, chamber 38 and bore 39.

As the pressure in the supply line 2 decreases or, in other words, as the volume of stored hydraulic fluid in the accumulator 23 is reduced, pressure on the piston 8 will, of course, be reduced, and the spring 19 will force the piston 8, pin 10 and spring guide 18 to the left, as viewed in Fig. 2 of the drawings, whereupon the snap spring 13 will again be compressed and this action will continue without movement of the piston 12 from its unloading position until the spacer tube 14 strikes the washer 11 which in response to continued movement to the left will produce the snap action movement of the piston 12, moving it from its unloading position to its loading position. This movement will cause the detent springs 17 to be rolled from the groove 20 to the open end groove 25.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A detent including a body having a cylindrical bore, a shiftable piston in said bore, a groove in said body, a pair of grooves in said piston selectively positionable opposite said body groove as said piston is shifted in said bore, a coil spring in said body groove having two ends contacting the bottom thereof and having a longitudinal axis which is normally substantially straight when said spring is released but which is curved by the action of said piston contacting it, said coil spring having direct contact at its inner center portion with said piston while being held in said body groove, said body groove having sufficient depth to permit said piston to deflect said spring while moving between its adjacent positions.
  2. A detent including a body, a shiftable member in said body, a cylindrical groove in said body, a cylindrical groove in said shiftable member, and a coil spring having two ends and a substantially straight axis when it is released and positioned in said two grooves with its center inner portion contacting the bottom of said cylindrical groove in said shiftable member groove and its ends contacting the bottom of said cylindrical body groove and being thereby bent into an arc of a circle, said coil spring bending into an arc of a circle of smaller diameter and rolling as said control member moves.
- 30 FRED J. WRIGHT.
